UNITED STATES PATENT OFFICE.

HARRY F. PORTER, OF TRENTON, NEW JERSEY, ASSIGNOR TO PYROELECTRIC INSTRUMENT CO., OF TRENTON, NEW JERSEY, A CORPORATION OF NEW JERSEY.

CONTROL APPARATUS.

1,377,274.

Specification of Letters Patent.

Patented May 10, 1921.

Application filed June 3, 1919. Serial No. 301,593.

To all whom it may concern:

Be it known that I, HARRY F. PORTER, a citizen of the United States, residing at 5 Trenton, county of Mercer, State of New Jersey, have invented a new and useful Control Apparatus, of which the following is a specification.

My invention relates to apparatus utilizable for recording variations of any character, for example temperature, or for effecting any suitable control in response to 10 effects produced by a device responsive to changes in a condition of any character, for example, temperature.

15 My invention resides in control or recording apparatus, preferably operating upon the null method, comprising a thermionic device, as an audion or equivalent, which responds to and amplifies electric current or 20 energy, particularly when of relatively small or minute magnitude, resulting from the subjection of a thermo-couple, resistance, or other suitable means, to changes in temperature or any other suitable or desired 25 condition.

In accordance with my invention there is produced a current or current change in response to a varying condition, as temperature, and as a result of such current or current 30 change the potential of a grid-like element is caused to effect a change in a thermionic or space current whose quantity attains different magnitudes for different grid potentials, and the plate or anode circuit 35 currents of different magnitudes effect a control of mechanism controlling either production of a record or any suitable apparatus, such, for example, as will in turn cause a change in the condition to which the grid 40 potential is responsive.

For an illustration of some of the various forms my invention may take, reference is to be had to the accompanying drawings, in which:

45 Figure 1 is a diagrammatic view illustrating recording apparatus embodying my invention.

Figs. 2, 3 and 4 are diagrammatic views of modified forms of apparatus embodying 50 my invention.

Fig. 5 is a view on enlarged scale of part of the structure employed in Fig. 1.

Fig. 6 is a graphic representation of relation between plate current and grid potential in a thermionic device.

Referring to Fig. 1, a potentiometer circuit is employed, as may be any equivalent thereof, comprising a source of current, as a battery B, connected in series with the resistances R, R¹ and R², the last named being 60 adjustable. T represents a junction of a thermo-couple adapted to be subjected to a temperature whose variations are to effect a record or control. The thermo-junction is connected through leads 1 and 2 with one 65 terminal of the resistance R and switch terminal 3, respectively. The contact a, movable along the resistance R by the nut b actuated by the screw c which is in turn rotated by the wheel or pulley d, is connected 70 by conductor 4 to the switch terminal 5. With the switch terminals 3 and 5 engage the switch blades 6 and 7 connected, respectively by conductors 8 and 9 with the electron-emitting body or filament f of the 75 audion A or any equivalent thermionic device, and the grid g interposed as usual between the electron-emitting body or cathode f and the plate or anode p. In the plate or anode circuit is any suitable source of 80 current, as battery B¹, and electro-magnet windings h and i. Coöperating with both sets of electro-magnets is an armature structure e, pivoted at j and adapted to engage the relay contacts k and m connected, 85 respectively, through conductors 10 and 11 with electro-magnets n and o, whose remaining terminals connect with a source of current, as battery B², whose other terminal connects with the relay armature j. Upon 90 a stationary pin p¹ is pivoted the armature lever q coöperating with the electro-magnets n and o. A gear or friction wheel r is rotatable coaxially with the pivot p and is driven by the pinion or friction wheels s 95 or adapted to be driven in one direction or the other as it is brought into contact with one or the other of the gears or friction wheels t or u, of which one, as t, is constantly rotated at uniform speed by a motor 100 or other suitable means, not shown, and wheel u is constantly driven by t. Movable with the nut b is a marker v, as a recorder pen or equivalent, marking upon the sheet of paper w stored in a roll upon roller w¹ and advanced past the marker v by engagement with the roller w² which is continuously driven at substantially constant speed by any suitable means, as for example, the motor which drives the wheel t. The 110

driving of the roller w^2 is indicated by the pulleys x , x^1 , x^2 and x^3 , with which coöperate suitable cords or belts, this being merely a diagrammatic indication of any 5 suitable means for rotating the roller w^2 .

- Movable laterally with respect to the aforesaid wheel or gear r are the gears or wheels d and y , the former adapted to rotate the aforesaid screw c and the latter 10 adapted to rotate the screw y^1 to move the nut y^2 longitudinally thereof to move the contact y^3 along the resistance R^2 for readjusting or calibrating the potentiometer circuit as hereinafter described. The wheels d 15 and y are pivoted, respectively, at 12 and 13 upon the transversely movable bar or member 14 biased toward the left by the spring 15 and carrying on its other end an armature 16 coöoperating with the electro-magnet 20 17, which latter is in circuit with the battery B^3 and the contact 18 adapted to engage once for each revolution of the wheel t the contact 19 carried by said wheel and connected to a slip ring 20 upon which bears 25 a brush 21 connected to the other terminal of the magnet 17.

Referring to Fig. 6, there is shown, by way of illustration merely, a characteristic curve of a thermionic device, ordinates representing anode or plate circuit currents, while abscissæ are grid potentials. It is seen that as the potential of the grid becomes more and more positive, the plate or anode current increases.

- 30 For any given anode or plate current, as z , corresponding, for example, with substantially zero potential of the grid g , as when the electro-motive-force of the thermo-couple T is equal and opposite to the electro-motive-force or fall of potential across that portion of the resistance R to the left of the contact a , the effects of the electro-magnets h and i in the anode or plate circuit may be made substantially equal and opposite, so 35 that the armature e remains in its mid-position indicated. One electro-magnet, as h , may have a greater number of convolutions or turns than the other and be so proportioned that with a predetermined or given 40 45 50 55 plate circuit current, as z , its magnetic circuit will be saturated, while the same current passing through the lesser number of turns of the magnet i causes it to produce magnetism substantially equal to the magnetism of the magnet h , but without saturation of the magnetic circuit of the magnet i .

The operation is as follows:

- When the temperature to which the junction T is subjected is such that the electro-motive-force produced by the thermo-couple balances the fall of potential across that part of the resistance R to the left of the contact a , the potential of the grid g is zero, or any 60 65 other suitable value if a source of current,

as one or more battery cells, is connected in the grid circuit. In any event, if this balance between the resistance and the thermo-couple T obtains, the aforesaid predetermined current z exists in the plate circuit and the armature e remains in its mid position indicated. If, however, the temperature and electro-motive-force of the thermo-couple increase, the fall of potential across the resistance R to the left of the point a is, for example, less than the thermo-couple electro-motive-force, and the potential of the grid g becomes, for example, more positive with increase of current in the plate or anode circuit to a value greater than the aforesaid value z . The magnet h being saturated, this increase of current will produce little or no increase in strength of the magnet h , but on the other hand, the strength of the magnet i will materially increase because its magnetic circuit is not saturated. Accordingly the balance between the magnets h and i is upset, and the magnet i will attract the armature e into engagement with the contact k , causing energization of the 9 electro-magnet n , which will then attract toward the right the upper end of the armature q , bringing the wheel s into engagement with the wheel u , rotating at substantially uniform speed, thereby causing the 9 wheel d to rotate the screw c in such direction as to move the nut b and the contact a toward the right until the fall of potential through the left hand portion of the resistance R again balances the now increased 10 electro-motive-force of the thermo-junction, whereupon the plate circuit current will return to its normal value and the armature e will return to its indicated mid position.

In effecting this movement of the nut b 10 the marker v has also moved transversely of the record sheet w to produce a record indicating an increase in temperature or electro-motive-force of the thermo-couple.

If the reverse condition obtains, that is, 11 the electro-motive-force of the thermo-couple diminishes to a value less than the fall of potential across the left hand portion of the resistance R , the plate circuit current will diminish below the value for a balance, 11 with the result that the magnet i will weaken much more than the saturated magnet h and magnet h will accordingly gain control of and attract armature e into engagement with contact m , causing energization of magnet o , 120 with the result that the wheel s will be brought into engagement with the wheel t and accordingly rotate the wheel d and screw c in opposite direction to that above referred to, causing the nut b , contact a and 125 marker v to move toward the left until balance is again reestablished.

And so on, the apparatus continues to operate automatically, moving the contact a and marker v backwardly and forwardly, 130

always seeking a balance between the electro-motive-force of the thermo-couple and the fall of potential through the portion of the resistance R to the left of contact a .

- 5 Where the battery B is not of the nature of a standard cell or a source whose electro-motive-force remains constant, as when the battery B is one or more dry cells, the electro-motive-force-current conditions in the 10 potentiometer circuit as affected by the battery B will vary from time to time and accordingly introduce errors. To overcome this, the apparatus comprises structure for readjusting the total resistance in series 15 with the battery B to such value that correct amount of current flows therethrough to effect the correct falls of potential across the left hand portion of the resistance R . This is accomplished as follows:—Once per 20 revolution of the wheel t the electro-magnet 17 is energized through the contacts 18 and 19, causing attraction of the armature 16, which moves the bar 14 to the right in opposition to the spring 15. This takes the wheel 25 d out of mesh or contact with the wheel r and brings wheel y into mesh or contact with wheel r . Simultaneously with the movement of the armature 16 toward the right, the mechanical connection 22 between the armature 16 and the switch 6, 7 moves the switch 6, 7 toward the right, bringing blades 6 and 7 into engagement, respectively, with the contacts 23 and 24, whereby there is brought into the grid circuit, in lieu of 30 the thermo-couple in coöperation with the left hand portion of the resistance R , the resistance R^1 and the standard cell S . The apparatus then operates automatically as before, for a period corresponding with the 35 angular extent of the contact 19, to seek and find a balance, and in so doing the wheel y is rotated in one direction or the other as the wheel s is in contact with one or the other of the wheels t or u , moving the contact y^3 40 to such point on the resistance R^2 that the fall of potential across the resistance R^1 due to current from the battery B is equal and opposite to the electro-motive-force of the standard cell S . By this action the resistance R^2 in series in the potentiometer 45 circuit has been adjusted to a new and correct value. Thereafter magnet 17 is deenergized, switch 6, 7 is returned to position indicated, wheel d resumes its indicated position, and 50 the apparatus again operates as above described.

In Fig. 2 an automatically controlled rheostat or resistance structure varies the current through a fixed resistance to vary 55 the drop of potential across said fixed resistance to balance the electro-motive-force of the thermo-couple or other equivalent device. In this instance the battery B is connected in circuit with a resistance R^3 around 60 a variable portion of which is shunted a

variable portion of the resistance R^4 in series with the aforesaid fixed resistance R^5 , and in series with the variable portion of resistance R^4 and the fixed resistance R^5 is any suitable galvanometer for indicating or 70 recording purposes. For example, the galvanometer may be a D'Arsonval galvanometer having the movable coil 25 whose pointer or needle 26 carries the marker v , coöperating with the recorder sheet w . In this instance there are movable with the nut b actuated by the screw c and wheel d the contacts a and a^1 movable, respectively, along the resistances R^3 and R^4 . In this case the wheel 75 d is coaxial with the pivot p^1 of the armature g , which coöperates with the magnets n and o , the wheel s driving the wheel d in one direction or the other as s engages one or the other of the wheels t or u , the magnets n and o being again controlled by the armature e coöperating with the plate circuit magnets h and i , as described in connection with Fig. 1. The thermo-couple or other device T is connected in the grid circuit in series with the resistance R^5 , whereby the 80 potential of grid g depends upon the electro-motive-force of the thermo-couple and the fall of potential across the resistance R^5 due to current from the battery B . The mode of operation is in general that described in 85 connection with Fig. 1 in that with rising and falling voltages of the thermo-couple the apparatus is unbalanced one way or the other, causing movement of the contacts a and a^1 in such direction as to restore a balance. For such balance at different 90 temperatures of the thermo-couple different currents are flowing through the galvanometer coil 25, causing different deflections of the needle 26 and therefore different transverse 95 positions of the marker v .

In addition to the coil 25 there may be inserted in circuit with the resistances R^4 and R^5 any number of galvanometers used either as indicators or recorders, or for any 100 other purposes.

In Fig. 3 a Wheatstone bridge arrangement is employed in which in adjacent arms on opposite sides of the movable contact a , moved by the wheel d , are the resistances 115 R^6 and R^7 ; in a third arm is the fixed resistance R^8 , and in the fourth arm is the thermometer resistance T^1 , which is subjected to the temperature to be measured or controlled, and accordingly varies its resistance in well known manner. The grid circuit of the thermionic device A is connected to the points 28 and 29, that is, in one conjugate conductor of the Wheatstone bridge 120 in whose other conjugate conductor is connected the battery B^4 .

In this case the operation is as follows:—

With a rise in temperature there is a rise 125 in resistance of the thermometer T^1 , causing a difference in potential between the points 130

28 and 29 with result that the wheel *d* is moved in one direction until the contact *a* readjusts the bridge to a balanced condition. The movement is accompanied by a movement of the marker *v* with respect to the marked sheet *w*. And similarly, with a falling temperature the reverse action will take place, the apparatus, as in Fig. 1, seeking a balanced condition and in so doing controlling a marker or any other suitable device.

In Fig. 4 is shown control apparatus whereby there may be automatically maintained substantially constant current through a resistance or other translating device. For example, the resistance *F* may be the resistor of an electric furnace through which it is desired to maintain a substantially constant current flow from the generator or source *G*, whose voltage is variable or which fluctuates from time to time. In series with the generator *G* and the resistance *F* is a resistance *R⁹* on which is movable a contact *b¹* connected to a resistance *R¹⁰* on which moves the contact *a* driven by the wheel *d* associated as before for control by the audion *A*. A variable portion of the resistance *R¹⁰* is connected in shunt to the resistance *F* and to a variable portion of the resistance *R⁹*, the contact *b¹* being manually moved to position to effect the predetermined current value which it is desired shall be maintained in the resistance *F*. The grid circuit of the audion includes the standard cell *S* and is connected in shunt to the resistance *F* or any desired portion thereof.

In operation, if the current through the resistance *F* should vary from the predetermined normal, the voltage of the grid *g* will be changed, effecting through the magnets *h* and *i* such a change in the plate or anode circuit current as to cause the wheel *d* to be moved in suitable direction to move the contact *a* to such position that the resistance *F* is suitably shunted to restore the current in the resistance *F* to the desired value. Thus, for either increases or decreases in the current in the resistance *F* the wheel *d* will be rotated in the one direction or the other to restore balance, which balance corresponds with the restoration of current in the resistance *F* to the predetermined desired amount.

It will be understood that the nut *b* or any other device moved as by the wheel *d* of any of the arrangements disclosed, or any equivalents thereof, may be used for moving valves, adjusting rheostats or effecting any other mechanical operation or control.

60 What I claim is:

1. The combination with an electrical source, of a thermionic device electrically controlled thereby, electrical means for producing a variable effect in opposition to the effect on said thermionic device produced

by said source, and means controlled by said thermionic device for varying said electrical means.

2. The combination with an electrical source, of a thermionic device electrically controlled thereby and comprising an electrode whose potential controls the magnitude of the space current, variable electrical means coöperating with said source to control the potential of said electrode, and means controlled by said thermionic device for varying said variable electrical means.

3. The combination with a temperature responsive device, of a thermionic device electrically controlled thereby, variable electrical means opposing said temperature responsive device in controlling said thermionic device, and means controlled by said thermionic device for varying said variable electrical means.

4. The combination with a temperature responsive device, of a thermionic device electrically controlled thereby and comprising an electrode whose potential controls the magnitude of the space current, variable electrical means coöperating with said temperature responsive device to control the potential of said electrode, and means controlled by said space current controlling said variable electrical means.

5. The combination with an electrical source, of a thermionic device electrically controlled thereby, variable electrical means coöperating with said electrical source in controlling said thermionic device, a source of power for actuating said variable electrical means, and means controlled by the space current of said thermionic device controlling said source of power.

6. The combination with an electrical source, of a thermionic device electrically controlled thereby, variable electrical means coöperating with said electrical source in controlling said thermionic device, a source of power for actuating said variable means, and means controlled by the space current of said thermionic device controlling connection between said variable electrical means and said source of power.

7. The combination with a temperature responsive device, of a thermionic device having an electrode whose potential controls the space current of said thermionic device, variable electrical means opposing said temperature responsive device in controlling the potential of said electrode, and means controlled by the space current of said thermionic device controlling said variable electrical means.

8. The combination with an electrical source, of a thermionic device, variable electrical means coöperating with said source in controlling said thermionic device, electro-magnetic means responsive, respectively, to increases and decreases in the space cur-

rent of said thermionic device controlling said variable electrical means.

9. The combination with an electrical source, of a thermionic device, variable electrical means coöperating with said electrical source in controlling said thermionic device, electro-magnetic means responsive, respectively, to increases and decreases in the space current of said thermionic device, and a source of power controlled by said electro-magnetic means for actuating said variable electrical means.

10. The combination with a temperature responsive device, of a thermionic device, variable electrical means coöperating with said temperature responsive device in controlling said thermionic device, electro-magnetic means responsive, respectively, to increases and decreases in the space current of said thermionic device controlling said variable electrical means.

11. The combination with a temperature responsive device, of a thermionic device, variable electrical means coöperating with said temperature responsive device in controlling said thermionic device, electro-magnetic means responsive, respectively, to increases and decreases in the space current of said thermionic device, and a source of power controlled by said electro-magnetic means for actuating said variable electrical means.

12. The combination with means responsive to temperature changes for effecting positive potential differences, of a thermionic device electrically controlled thereby and comprising an electrode whose potential controls the space current of said thermionic device, means for producing a variable potential in opposition to the potential difference effected by said temperature responsive device and coöperating therewith to control the potential of said electrode, and means controlled by said space current controlling said variable electrical means.

13. The combination with a thermo-couple, of a potentiometer comprising a variable resistance to produce a fall of potential equal and opposite to the electro-motive force produced by said thermo-couple, a thermionic device having an electrode whose potential depends upon the difference of the electro-motive forces produced by said thermo-couple and potentiometer for controlling the space current of said thermionic device, and means controlled by said space current for adjusting the fall of potential in said potentiometer to equality with the electro-motive force produced by said thermo-couple.

14. The combination with a source of current, of electrical means associated therewith for determining the magnitude of current flowing therefrom, mechanical means for varying the magnitude of said electrical

means, a source of power for mechanically actuating said mechanical means, and a thermionic device electrically controlling connection between said mechanical means and said source of power and responsive to variation of said mechanical means.

15. The combination with a resistance, of mechanical means for varying the amount of said resistance in a circuit, a thermionic device, a source of power, means for connecting said source of power with said mechanical means and electrically controlled by said thermionic device, said thermionic device being controlled in response to variation of said first-named mechanical means.

16. The combination with an electrical source, of a thermionic device electrically controlled thereby, variable electrical means opposing said responsive device, means controlled by said thermionic device for varying said variable electrical means, and a marker simultaneously controlled by said thermionic device.

17. The combination with an electrical source, of a thermionic device electrically controlled thereby and comprising an electrode whose potential controls the magnitude of the space current, variable electrical means coöperating with said source to control the potential of said electrode, means controlled by said thermionic device for varying said variable electrical means, and a marker simultaneously controlled by said thermionic device.

18. The combination with a temperature responsive device, of a thermionic device electrically controlled thereby, variable electrical means opposing said temperature responsive device, means controlled by said thermionic device for varying said variable electrical means, and a marker simultaneously controlled by said thermionic device.

19. The combination with a temperature responsive device, of a thermionic device electrically controlled thereby and comprising an electrode whose potential controls the magnitude of the space current, variable electrical means coöperating with said temperature responsive device to control the potential of said electrode, means controlled by said space current controlling said variable electrical means, and a marker simultaneously controlled by said thermionic device.

20. The combination with an electrical source, of a thermionic device electrically controlled thereby, variable electrical means coöperating with said responsive device in controlling said thermionic device, a source of power for actuating said variable electrical means, means controlled by the space current of said thermionic device controlling said source of power, and a marker actuated by said source of power.

21. The combination with an electrical source, of a thermionic device electrically

- controlled thereby, variable electrical means coöperating with said electrical source in controlling said thermionic device, a source of power for actuating said variable electrical means, means controlled by the space current of said thermionic device controlling connection between said variable electrical means and said source of power, and a marker simultaneously controlled by said 10 thermionic device.
22. The combination with an electrical source, of a thermionic device, variable electrical means coöperating with said electrical source in controlling said thermionic device, 15 electro-magnetic means responsive, respectively, to increases and decreases in the space current of said thermionic device, a source of power controlled by said electro-magnetic means for actuating said variable electrical 20 means, and a marker actuated by said source of power.
23. The combination with means responsive to temperature changes for effecting potential differences, of a thermionic device 25 electrically controlled thereby and comprising an electrode whose potential controls the space current of said thermionic device, means for producing a variable potential in opposition to the potential difference effected by said temperature responsive device 30 and coöperating therewith to control the potential of said electrode, means controlled by said space current controlling said variable means, and a marker controlled by said 35 space current.
24. The combination with a thermionic device having an electrode controlling the space current of said device, a circuit traversed by said space current, a movable 40 member, a source of power, means for connecting said source of power with said movable member to move the same, means controlled by said circuit controlling said connecting means, and means for varying the 45 potential of said electrode.
25. The combination with a thermionic device having an electrode whose potential controls the space current, a circuit traversed by said space current, a movable 50 member, means for moving the same, means in said circuit controlling said last named means, and means actuated by said movable member for varying the potential of said electrode.
55. 26. The combination with a thermionic device having an electrode whose potential controls the space current, a circuit traversed by said space current, electro-magnetic means controlled by said circuit, a movable 60 member, a source of power, means for connecting said source of power with said movable member and controlled by said electro-magnetic means, and means for changing the potential of said electrode.
65. 27. The combination with a thermionic device having an electrode whose potential controls the space current, a circuit traversed by said space current, and electro-magnetic means in said circuit responsive, respectively, in opposite directions to 70 changes of said space current in opposite directions, said means comprising an armature member, normally saturated and unsaturated electro-magnets coöperating with said armature member, and means for 75 changing the potential of said electrode.
28. The combination with a thermionic device, of a circuit traversed by the space current thereof, and means associated with said circuit and responding in opposite directions to changes in opposite directions of said space current comprising normally saturated and unsaturated electro-magnets, and an armature member coöperating therewith.
85. 29. The combination with a source of variable potential, of a thermionic device having an electrode whose potential controls the space current of said device, said electrode being connected with said source of 90 variable potential, a movable structure, a source of power, means actuated by said space current controlling actuation of said movable structure by said source of power, and a resistance varied by said movable 95 structure and opposing said variable potential.
30. The combination with a source of variable potential, of a thermionic device having an electrode whose potential controls 100 the space current of said device, said electrode being connected with said source of variable potential, a movable structure, a source of power, means controlled by said space current connecting said movable 105 structure with said source of power, and a marker moved by said movable structure.
31. The combination with a source of variable potential, of a thermionic device having an electrode whose potential controls 110 the space current of said device, said electrode being connected with said source of variable potential, a movable structure, a source of power, means controlled by said space current connecting said movable 115 structure with said source of current, a variable resistance opposing variations of said variable potential actuated by said movable structure, and a marker moved by said movable structure.
120. 32. The combination with a source of variable potential, of a thermionic device having an electrode whose potential controls the magnitude of current in the anode circuit of said device, said electrode being subjected to potential variations of said source, a movable structure, a source of power, means controlled by said current controlling actuation of said movable structure by said source of power, and current 125
- 130.

controlling means operated by said movable structure.

33. The combination with a source of variable potential, of a thermionic device having an electrode whose potential controls the magnitude of current in the anode circuit of said device, said electrode being subjected to potential variations of said source, a movable structure, a source of power, means controlled by said current controlling actuation of said movable structure by said source of power, current controlling means operated by said movable structure and a second source of variable potential opposing said first named source and controlled by said movable structure.

34. The combination with a thermo-couple, of a thermionic device having an electrode whose potential controls the magnitude of current in the anode circuit of said device, said electrode being subjected to voltage variations of said thermo-couple, a movable structure, a source of power, means controlled by said current controlling actuation of said movable structure by said source of power, and a source of variable potential opposing said thermo-couple and controlled by said movable structure.

35. The combination with a thermo-couple, of a thermionic device having an electrode whose potential controls the magnitude of current in the anode circuit of said device, said electrode being subjected to voltage variations of said thermo-couple, a movable structure, a source of power, means controlled by said current controlling actuation of said movable structure by said source of power, a source of variable potential opposing said thermo-couple and controlled by said movable structure, and a marker actuated by said movable structure.

36. The combination with a source of variable potential, of a thermionic device having an electrode controlling the current in the anode circuit of said device, the potential of said electrode being controlled by said source, a movable structure, a source of power, means controlling actuation of said movable structure by said source of power, and relay means controlled by the current in the anode circuit of said thermionic device controlling said means.

In testimony whereof I have hereunto affixed my signature this 17th day of May, 1919.

HARRY F. PORTER.
